STORE-FRONT CONSTRUCTION

Fred Himmel and Isidore Himmel, New Haven,
Conn., assignors to The Himmel Brothers
Company, New Haven, Conn., a corporation

Application February 2, 1932. Serial No. 590,342

2 Claims. (Cl. 20—56.4)

This invention relates to an improvement in store-front constructions and particularly to constructions which include a rear member and a front member, the two being connected by a screw 5 passing through the front member and into a window-casing. In such constructions, it is desirable that some means should be provided for preventing the edge of the glass from coming in contact with the screws and it is also desirable that 10 the outer member should be reinforced to hold the outer edge of the outer member against the glass.

The object of this invention is to provide means for accomplishing this purpose and the invention 15 consists in the construction as hereinafter described and particularly recited in the claims.

In the accompanying drawings:

Fig. 1 is a front view of a store-front construction embodying our invention; 20 Fig. 2 is a sectional view on the line 2—2 of Fig. 1;

Fig. 3 is a perspective view of a portion of an outer member;

Fig. 4 is a perspective view of a portion of an 25 inner member;

Fig. 5 is a perspective view of a brace for the outer member, detached;

Fig. 6 is a front view of a modified form of our 30 invention;

Fig. 7 is an edge view of the same; 35 Fig. 8 is a sectional view on the line 8—8 of Fig. 6;

Fig. 9 is a perspective view of a section of the outer member of a modified form, detached;

Fig. 10 is a perspective view of a section of the 40 inner member shown in Figs. 6, 7 and 8; and

Fig. 11 is a perspective view of the brace used with the construction shown in the figures last mentioned.

In carrying out our invention, we employ an 45 inner member 15 of substantially usual form except that from the base 16 a stop 17 is provided, this stop being cut from the base and turned outward therefrom. The outer member 18 is of any approved design and includes a base 19, a shoulder 20 and a pocket 21, which bears against a sheet of glass 22.

To reinforce the outer member, we employ a brace 23 having an upwardly-extending arm 24 50 to enter the pocket 21, an outwardly-extending arm 25 to engage with the shoulder 20, with a transverse notch 26 in its under-face into which is entered a rib 27, struck upward from the base 19, and an inwardly-extending finger 28 to engage 55 with the stop 17. The parts are connected to-

gether by a screw 29 extending through the front, through a hole 30 in the brace, and into the window-casing 31. The brace is also preferably formed with a shelf 32 which may not only form a support for the glass, but prevents the 60 edge of the glass from coming in contact with the screw.

Instead of forming the stop 17 as an integral part of the inner member, the stop for the finger 28 may be a tubular member 33, as shown in Figs. 65 7, 8 and 10 of the drawings. This tubular member forms a support for the glass and prevents it from coming in contact with the screw and the lower wall 34 forms a stop for the finger 28 and so tends to hold the outer member in close 70 contact with the glass, as in the construction first described.

Instead of forming the rib 27, the outer strip may be formed at its inner edge with a lip 35 to enter the notch 26 in the brace. In either 75 construction, it will be seen that the brace is interlocked with the outer member and that means are provided for firmly clamping the outer member against the glass, and also that means are provided for preventing the edge of the glass 80 from coming in contact with the screw.

We claim:

1. A store-front construction comprising inner and outer members, a brace connected with the outer member and interlocked therewith, said 85 brace formed with an inwardly-projecting finger and an inwardly-projecting shelf, and the inner member provided with a stop to be engaged by said finger, and means for clamping the outer member against the inner member. 90

2. A store-front construction comprising inner and outer members, the outer member comprising a base, a shoulder and a pocket, a brace comprising an arm extending into said pocket, a base interlocked with the base of the said outer member 95 and formed with an outwardly-extending arm engaging with the said shoulder, said brace also formed with an inwardly-extending bowed finger, the inner member having a base formed with an upwardly and forwardly extending bowed stop, 100 beneath which said finger extends so as to be engaged therewith, and means for securing the outer member in place and crowding it against a sheet of glass. 105
